UNITED STATES PATENT OFFICE.

DAVID H. STROUD, OF PHILADELPHIA, PENNSYLVANIA.

MACHINE FOR TREATING CUT PILE FABRICS.

1,344,777.

Specification of Letters Patent. Patented June 29, 1920.

Application filed January 18, 1917. Serial No. 142,992.

To all whom it may concern:

Be it known that I, DAVID H. STROUD, of Philadelphia, in the county of Philadelphia and State of Pennsylvania, have invented 5 certain new and useful Improvements in Machines for Treating Cut Pile Fabrics, whereof the following is a specification, reference being had to the accompanying drawings.

10 The invention relates to machines for treating cut pile fabrics, such as chenille, Axminster and Wilton rugs, and the like.

Heretofore it has been customary in the treatment of such fabrics to submit them 15 to the action of stiff bristle brushes for the purpose of removing the loose fibers and alining the pile fibers. This treatment has proved successful in removing some of the loose fibers, but it is impossible to remove 20 them all in this manner. I have found, however, that by subjecting the fabric to a stiff scraping by a roll covered with sand paper, or other similar abrasive, it is possible to thoroughly separate the fibers and 25 remove the short strands. Furthermore, this treatment not only cleans and softens the fabric, but also serves to cause intermingling of the strands of adjacent varicolored tufts of the nap, which results in the 30 assimilation of the colors, giving the appearance of the finest type of antique oriental rug.

It is an object of my invention to provide 35 a machine in which fabrics of this sort may be subjected to such abrasive treatment, which is at the same time both simple and efficient.

A further object is to provide means 40 whereby the fabric being treated may be moved into or out of contact with the abrasive at the will of the operator.

A still further object is to provide means whereby any of the parts of said machine 45 may be rendered temporarily ineffective without interfering with the operation of the other parts.

Referring to the accompanying drawings, Figure I, is a plan view of a machine constructed according to my invention.

50 Fig. II, is a side view of the same as seen from the left of Fig. I.

Fig. III, is a central cross section indicated by the arrows III—III in Fig. I.

In carrying out my invention I provide

standards 1, and 2, united by suitable tie 55 rods 3, and 4. Driving shaft 5, is mounted in suitable bearings 6, and 7, on standards 1, and 2, respectively. Intermediate these standards shaft 5, carries scouring roll 8, which is securely attached thereto, and covered with sand paper or other similar abrasive. 60

Pulley 10, is loosely mounted on the end of shaft 5, projecting beyond standard 2, while pulley 11, is loosely mounted on the other 65 end. Pulley 10, is connected with any appropriate source of power (not shown) and serves to drive shaft 5, by means of clutch 13. Clutch 13, is slidably mounted on shaft 5, and connected at 15, to arm 14, which is 70 in turn pivoted at 16, to V shaped support 17, which extends outwardly from standard 2. Arm 14, is also pivoted at 18, to rod 20, which is slidably supported in a position parallel to shaft 5, by uprights 21, and 22, 75 which extend upwardly from standards 1, and 2, respectively. Consequently, any movement of rod 20, to the left transmits a similar movement to clutch 13, serving to clutch pulley 10, to shaft 5, while a reverse 80 movement of rod 20, to the right releases them.

Loose pulley 11, is also controlled by a similar clutch 25, loosely mounted on shaft 5, between pulley 10, and standard 1, and 85 connected to arm 26, at 27. Arm 26, is in turn pivoted at one end by bolt 28, to bracket 29, extending outwardly from standard 1, and at the other to rod 30, by means of pin 31. In this way pulley 11, may be clutched 90 or released by moving rod 30, either to the left or right.

Pulley 11, carries belt 35, thereby driving wheel 36, mounted on stud shaft 37. Also mounted on shaft 37, is pinion 38, intermeshing with gear 39, mounted on shaft 40, which extends between standards 1, and 2. Pinions 44, and 45, are mounted on either end of shaft 40, and serve to drive sprocket wheels 46, and 47, by means of chains 48, 100 and 49, respectively. Sprocket wheels 46, and 47, are mounted on studs 51, and 52, projecting from standards 1, and 2, and carry pinions 53, and 54. Pinions 53, and 54, intermesh with gears 55, and 56, mounted on 105 either end of shaft 57, pivoted in standards 1, and 2, and which carries spiked feed roller 59, intermediate the two standards.

In this way roller 59, is driven from both ends, which does away with any torsional strain such as might result in warping or uneven motion.

5 At the opposite side of the machine, loose spiked roller 60, is similarly mounted intermediate standards 1, and 2, on shaft 62, which carries pulleys 63, and 64, at either end. Over pulleys 63, and 64, pass weighted 10 strips 65, and 66, which are attached at one end to studs 67, and 68, projecting from standards 1, and 2, respectively. These strips serve as brakes to constantly maintain the fabric under tension during its passage 15 through the machine.

Mounted directly under roll 8, is ledger bar 70. This bar has a flat surface which extends the whole length of roll 8, and is attached at its ends to slide bars 71, and 72, 20 which are adapted to slide in guides formed in lugs 73, and 74, projecting from standards 1, and 2, respectively. The lower ends of slide bars 71, and 72, are pivotally connected to arms 75, and 76, which are in turn 25 rigidly attached to rock shaft 78, journaled in standards 1, and 2, respectively. To the outer ends of shaft 78, are rigidly attached treadles 81, and 82, which project outwardly beyond feed roller 59. Treadles 81, and 82, 30 are provided with counterweights 83, and 84, which tend to counteract the weight of ledger bar 70, but are not heavy enough to overbalance it. By depressing either of the treadles to the position shown in the drawings, ledger bar 70, is raised to the position 35 shown in Fig. III, where it is just short of contact with roll 8, being limited at this point by set screw 88 (see Fig. II) whereby the distance between bar 70, and scouring 40 roll 8, may be regulated with great nicety. Bar 70, is also limited in its downward motion by stop 89, (see Fig. III) set on slide bar 72, in such a position as to come in contact with lower lug 74, when a convenient 45 lower position of the ledger bar is reached.

In operation, the fabric 90, to be treated is passed over loose roller 60, to feed roller 59, and clutches 13, and 25, thrown in so that rolls 8, and 59, are both rotated. Feed 50 roller 59, however, rotates much more slowly than roll 8, as a result of the chain of gearing described, thus progressing fabric 90, slowly in the direction of the arrows. Either treadle may then be depressed so as 55 to bring ledger bar 70, into its upper position, and bring fabric 90, into contact with the lower edge of scouring roll 8, which is moving in the opposite direction to that of the fabric and at a much greater speed. In 60 this way the pile tufts are separated by the abrasive carried by roll 8, so that the short strands of the nap are removed. At the same time, due to the fact that the fabric and the lower edge of roll 8, move in the opposite direction, the pile fibers or nap of the

fabric which formerly occupied approximately upright or indiscriminate positions, are now all laid in the same direction in the position shown in Fig. III.

While the fabric is being thus progressed, the friction due to weighted straps 65, and 66, prevents loose roller 60, from rotating too quickly and holds the fabric taut. This is especially useful when the opposing force of roll 8, is first applied, as it has a tendency to slow up the travel of the rug. In this way I preserve an absolutely even travel of the fabric, while at any time it may be withdrawn from contact with scouring roll 8, by simply allowing the treadles to rise and ledger bar 70, to sink to its normal position. At the same time it is also possible to stop the travel of the fabric by moving rod 30, to the right and throwing out clutch 25, while the whole machine is stopped by 85 throwing out clutch 13.

It will be noticed that this operation also is accomplished by moving rod 15, to the right, so that both clutches are thrown out by the movement of their respective bars in 90 one direction and thrown in by movement in the other direction, so that since the bars are placed in proximity a very simple and effective form of control is provided. Treadles 81, and 82, are also located on the 95 same side of the machine as rods 20, and 30, and project outwardly from the standards sufficiently beyond roller 59, to permit one person standing on that side of the machine to operate both the rods and treadles. 100

Having thus described my invention, I claim:

1. In a machine for treating cut pile fabrics and the like, the combination of a loose roller, a feed roller adapted to progress a 105 fabric thereover, a scraping roll with continuous abrasive surface mounted above said rollers, and means mounted below and between said rollers movable upward and downward to bring the surface of the fabric into contact with the scraping roll, and vice-versa.

2. In a machine for treating cut pile fabrics and the like, the combination of a feed roller adapted to progress a fabric, a scraping roll with continuous abrasive surface mounted above said feed roller, a flat surface mounted below said feed roller, and means for raising and lowering said flat surface to bring the surface of the fabric 110 into contact with said scraping roll, and vice-versa.

3. In a machine for treating cut pile fabrics and the like, the combination of a rotary feed roll for progressing the fabric, a 125 braked roll transmitting the fabric to said feed roll, a rotary scraping roll with continuous abrasive surface moving in the opposite direction to the fabric, and a ledger bar at the other side of the fabric from said 130

scraping roll movable toward and away therefrom to bring the fabric into contact therewith, and vice versa.

4. In a machine for treating cut pile fabrics and the like, the combination of a feed roller for progressing a fabric, a scraping roll with continuous abrasive surface mounted so as to come in contact with the surface of the fabric, means for providing a rigid backing for said fabric as it passes in contact with said scraping roll, and means for rotating said scraping roll so that the portion in contact with the fabric is moving at a greater speed than the fabric.

5. In a machine for treating cut pile fabrics and the like, the combination of a feed roller for progressing a fabric, a scraping roll with continuous abrasive surface mounted so as to come in contact with the surface of the fabric, means for providing a rigid backing for said fabric as it passes in contact with said scraping roll, and means for rotating said scraping roll opposite to the direction in which the fabric progresses.

6. In a machine for treating cut pile fabrics and the like, the combination of a feed roller for progressing a fabric, a scraping roll with continuous abrasive surface mounted so as to come in contact with the surface of the fabric, means for providing a rigid backing for said fabric as it passes in contact with said scraping roll, and means for rotating said scraping roll so that the portion in contact with the fabric is moving at a greater speed than the fabric and in the opposite direction thereto.

7. In a machine for treating cut pile fabrics and the like, the combination of a pair of standards, a driving shaft loosely mounted therein, a scraping roll mounted on said driving shaft between said standards; a feed roller mounted between said standards below said scouring roll, a pulley loosely mounted on said driving shaft, means for clutching said pulley to said shaft, a belt carried by said pulley, a wheel driven thereby, a pinion mounted on said wheel, a shaft journaled in said standards, a gear on one end of said shaft intermeshing with said pinion, sprocket wheels on both ends of said shaft and connections whereby said feed roller is driven at both ends by said sprockets.

8. In a machine for treating cut pile fabrics and the like, the combination of a pair of standards, a driving shaft loosely mounted therein, a scraping roll mounted on said driving shaft between said standards; a feed roller mounted between said standards below said scraping roll, a pulley loosely mounted on said driving shaft, means for clutching said pulley to said shaft, a belt carried by said pulley, a wheel driven thereby, a pinion mounted on said wheel, a shaft

journaled in said standards, a gear on one end of said shaft intermeshing with said pinion, sprocket wheels on both ends of said shaft and sprocket wheels mounted on said standards in proximity to the ends of said feed roller driven by chains from said first mentioned sprockets; pinions carried by said second mentioned sprockets and intermeshing with gears on the ends of said feed roller, whereby said feed roller is driven at a much slower rate than said scraping roll and in the opposite direction thereto.

9. In a machine for treating cut pile fabrics and the like, the combination of a pair of standards, a driving shaft loosely mounted therein, a scraping roll mounted on said driving shaft between said standards, a feed roller mounted between said standards below said scraping roller, and a pulley loosely mounted on one end of said driving shaft, means for clutching said pulley to said shaft, connections whereby said feed roller is driven by said pulley at a much slower rate than the scraping roll and in the opposite direction thereto, said clutching means being slidably mounted on said driving shaft, an arm pivoted thereto, a rod pivoted to said arm and mounted in parallel relation to said driving shaft in such a position that longitudinal movement of said rod controls said clutching means.

10. In a machine for treating cut pile fabrics and the like, the combination of a pair of standards, a driving shaft loosely mounted therein, a scraping roll mounted on said driving shaft between said standards, a feed roller mounted between said standards below said scouring roll, and a pulley loosely mounted on one end of said driving shaft, means for clutching said pulley to said shaft, connections whereby said feed roller is driven by said pulley at a much slower rate than the scraping roll and in the opposite direction thereto, said clutching means being slidably mounted on said driving shaft, an arm pivoted thereto, uprights mounted on said standards, and a rod slidably mounted in said uprights parallel to said driving shaft, said rod being pivoted to said arm in such a manner that any movement of the rod moves the clutching means in the same direction.

11. In a machine for treating cut pile fabrics and the like, the combination of a pair of standards, a driving shaft loosely mounted therein, and projecting therethrough, a scraping roll mounted on said driving shaft between said standards, a feed roller mounted between said standards below said scraping roll, a pulley loosely mounted on each end of said driving shaft, without the standards, one of said pulleys being connected with a source of power and the other with the feed roller, means adapted to clutch each of said pulleys to said shaft; a pair of

rods connected one with each of said clutching means and mounted in parallel relation in such a manner that movement of both of said rods in the same direction either 5 clutches or releases both of said pulleys.

12. In a machine for treating cut pile fabrics and the like, the combination of a pair of standards, a driving shaft loosely mounted therein, a scraping roll mounted on said 10 driving shaft, a feed roller adapted to progress a fabric mounted in said standards below said scraping roll; a pulley loosely mounted on each end of said driving shaft, one of said pulleys being connected 15 with a source of power and the other with the feed roller; means adapted to clutch each of said pulleys to said shaft; a pair of rods connected one with each of said clutching means and mounted in parallel relation

above said feed roller, so as to be capable of 20 longitudinal motion only and in such a manner that movement of both of said rods in the same direction either clutches or releases both said pulleys; and means for raising said fabric and bringing it into contact with said scraping roll, said means including a treadle pivoted to one of said standards below said rods and projecting outwardly therefrom beyond said feed roller, in such a manner that both treadles 25 and rods may be operated by one person.

In testimony whereof, I have hereunto signed my name at Philadelphia, Pennsylvania, this ninth day of January, 1917.

DAVID H. STROUD.
